FOLLOWER FOR CARD DRAWERS OR THE
LIKEForest L. W. Link, Silverton, Ohio, assignor to The
Globe-Wernicke Company, Norwood, Ohio, a
corporation of Ohio

Application December 19, 1938, Serial No. 246,584

2 Claims. (Cl. 129—30)

This invention relates to followers of the type generally used in connection with card index drawers, although the follower construction is applicable to any type of drawer or case in which it is desired to use a follower. This follower will be described herein in connection with a drawer of the type having a longitudinal rod, adapted for use with index cards having a perforated tab extending from the bottoms thereof.

Followers of the general class outlined above must lock with the case or drawer in any position in which they may be placed, and yet must be capable of adjustment longitudinally of the drawer. For this purpose it is necessary to provide some readily releasable locking arrangement. Various such arrangements are known in the art, and it is an object of this invention to provide one such arrangement which will embody numerous advantages.

The objects of my invention, generally speaking, include the provision of a novel follower construction in which a minimum of separate parts are used, in which the individual parts are of simple construction and may be easily assembled, and the provision of such a construction which will be very inexpensive to manufacture, but which will nevertheless satisfy to a high degree the demands of commercial use.

These and other objects of the invention which will be described in more detail hereinafter, or which will be apparent to one skilled in the art upon reading these specifications, I accomplish by that certain construction and arrangement of parts, of which I shall now describe an exemplary embodiment. Reference is now made to the drawing forming a part hereof, and in which:

Figure 1 is a perspective view, with parts broken away for clarity of illustration, of a drawer and a follower therein;

Fig. 2 is a cross-sectional view taken on the line 2—2 of Fig. 1;

Fig. 3 is a cross-sectional view taken on the line 3—3 of Fig. 2;

Fig. 4 is a perspective view, taken from the rear, of the follower plate; and

Fig. 5 is a perspective view of the locking lever.

Briefly, in the practice of my invention, I provide a drawer 10 of conventional construction, provided with a central, longitudinal groove 11, along which extends a rod 12. Means (not shown) are provided whereby the rod 12 may be removed so that cards may be threaded thereon, the cards for that purpose being provided with perforated tabs to receive the rod 12 and fit within the groove 11.

The follower itself I prefer to make from only three pieces: the follower plate 13, the locking lever 14, and the spring 15. The plate 13 is generally of the shape of the cards carried in the drawer. It is provided with a tab portion 16 having a perforation 17 to receive the rod 12, and may be provided with a formed thumb grip portion 18. In order to maintain it in erect position, I provide it with what I shall term an outrigger element 19. As will readily be seen from Fig. 4, 10 the element 19 is formed by striking out from the body of the plate 13 an inverted T shaped portion and bending it rearwardly about its lower edge. The horizontal element 20 of the said T shaped portion extends horizontally rearward, 15 and the downwardly extending element 21 is bent downwardly at an angle, and the terminal vertical portion 21a thereof is bent to be substantially parallel to the plate 13. The portion 21a is perforated at 21b to receive the rod 12, and the portions 20 and 21 are strengthened by means of the formed up ribs 20a. The perforations 17 and 21b are somewhat oversize with reference to the rod 12 so that the plate 13 with its outrigger 19 may easily slide back and forth along the 25 rod 12.

The locking lever consists of a flat piece having at its lower end a projecting tab 14a similar in size and shape to the tab 16 on the plate 13, and the tab 14a is similarly perforated at 14b. 30 A slot 14c is provided, said slot corresponding in shape to a cross-section through the portion 21 of the outrigger.

The respective parts are assembled on the rod 12 as best seen in Fig. 3 with the spring 15 surrounding the rod between the outrigger portion 21a and the locking lever tab 14a. It will be clear from a consideration of Fig. 3 that the locking lever 14 may pivot about the line 22 on the outrigger, and is urged in a clockwise direction by the spring 15 so that the lower edge of the perforation 14b binds against the rod 12, locking the follower against movement in the drawer. In order to release the follower it is only necessary to grasp the upper end of the 40 locking lever 14 and the thumb grip 18 between the thumb and forefinger of one hand, thereby rocking the locking lever 14 counterclockwise against the spring 15 to a generally vertical position where the perforation 14b no longer binds 50 against the rod 12. The follower may then be shifted to any desired position.

The parts are preferably made of sheet metal, although other materials may be used. Likewise the plate and outrigger might be made separately. 55

It will be readily understood that various modifications will present themselves to the man skilled in the art and that such modifications may be made without departing from the spirit of my invention. I therefore do not intend to limit myself otherwise than as pointed out in the claims which follow.

Having now fully described my invention, what I believe to be new, and desire to protect by Letters Patent, is:

1. A follower for a filing drawer having a longitudinal rod, comprising a follower plate having a rod receiving aperture, an inverted T-shaped portion struck out from said plate and bent rearwardly and the leg portion of said T-shaped portion being bent downwardly to form an outrigger, a rod receiving aperture in said outrigger, and a locking lever having a rod receiving aperture and a slot therein, said slot being of a width to accommodate only said leg portion and being thereby pivoted against the head

of said T-shaped portion, and means urging said lever to a non-vertical position whereby to cause the rod receiving aperture to bind against said rod.

2. A follower for a filing drawer having a longitudinal rod, comprising a follower plate having a rod receiving aperture, an inverted T-shaped portion struck out from said plate and bent rearwardly and the leg portion of said T-shaped portion being bent downwardly to form an outrigger, a rod receiving aperture in said outrigger, said outrigger having a rib formed therein, and a locking lever having a rod receiving aperture and a slot therein, said slot having a portion to accommodate said rib and being of a width to accommodate only said leg portion and being thereby pivoted against the head of said T-shaped portion, and means urging said lever to a non-vertical position whereby to cause said rod receiving aperture to bind against said rod.
